(57) **CLAIM**

The ornamental design for a personal wireless hotspot device, as shown and described.

DESCRIPTION

FIG. 1 is a front perspective view of an embodiment of the new design;

FIG. 2 is a front elevational view of the new design;

FIG. 3 is a bottom perspective view of the new design;

FIG. 4 is a rear elevational view of the new design;

FIG. 5 is a left side elevational view of the new design;

FIG. 6 is a right-side elevational view of the new design;

FIG. 7 is a top plan view of the new design; and,

FIG. 8 is a bottom plan view of the new design.

1 Claim, 4 Drawing Sheets
